BENDING BALL ARBOR

Frank M. Check, Sr., Stratford, Conn.

Application June 21, 1946, Serial No. 678,430

4 Claims. (Cl. 153—63)

1

This invention relates to a bending ball arbor, and more particularly to such an arbor adapted to be utilized when bending tubular material.

A primary object of this invention is the provision of an improved bending ball arbor, or articulated mandrel, adapted to be positioned interiorly of the tubing during the process of bending to insure a relatively smooth and accurate bend in the tube.

A further object of the invention is the provision of such an arbor which may be advantageously utilized in the formation of bends in tubing of relatively small radius.

A further and very important object of the invention is the provision of such a device characterized by links securing the several balls in related assembly, the links being held in position by pins which do not extend exteriorly of the balls, thus obviating the possibility of accidental displacement of a pin, or pins, during the bending operation, and consequent spoilage of the tubing and breakage of the bending apparatus.

A still further object of the invention is the provision of such a device which is sturdy and durable in construction, reliable and efficient in operation, and relatively simple and inexpensive to manufacture and assemble.

Other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a fragmentary longitudinal sectional view taken substantially along the center line of one form of arbor embodying the instant inventive concept.

Figure 2 is a transverse sectional view taken substantially at right angles to the section shown in Figure 1, or along the line 2—2 of Figure 1.

Figure 3 is an enlarged side view partially in elevation and partially in section, showing the application of the arbor within a tube in the process of bending.

Figure 4 is a sectional view taken substantially along the line 4—4 of Figure 1.

Figure 5 is an enlarged perspective view of one of the links connecting adjacent balls.

Figure 6 is a longitudinal sectional view, partially in elevation, through a modified form of apparatus.

Figure 7 is a continuation of Figure 6, showing the method of securing the rear ball to the operating shaft of the apparatus.

Figure 8 is a sectional view taken substantially along the line 8—8 of Figure 6, as viewed in the direction indicated by the arrows.

Figure 9 is a sectional view taken substantially

along the line 9—9 of Figure 7, as viewed in the direction indicated by the arrows.

Similar reference characters refer to similar parts throughout the several views of the drawings.

Referring now to the form of device disclosed in Figures 1 to 5, inclusive, there is generally shown at 10 a tubular rigid shank member having a central bore 11, within which is positioned a collar 12 having an extending shank 13 adapted to be secured in any desired manner to conventional apparatus. The collar 12 includes a centrally positioned aperture or recess 14, within which is positioned a bifurcated member 15, apertured to receive a pin 16, which extends transversely of the aperture the full diameter of the bore 11 and is seated in the collar 12. The pin is adapted to pass through a suitable aperture in an extending shank 17 comprising a portion of a link generally indicated at 18, see Figure 5, provided with bifurcations 19 having apertures therein for the accommodation of a pin 20 corresponding to the pin 16.

The ends of the pin 20 are adapted to seat in grooves 22 cut interiorly in a bore in a "ball" segment of generally toric configuration, and generally indicated at 23. The grooves 22 open through the front surface of each ball to permit the insertion and removal of the pin 20. The outer surface of the member 23 is of circular configuration in transverse section, as indicated at 23', Figure 4.

The bifurcations 19 of the link 18 accommodate the shank 17 of an identical link provided with a similar aperture 17' through which is passed a second pin 20 seated in interior grooves 22 of the adjacent "ball" 23. Successive "balls" 23 are secured in an identical manner for a desired length of bendable character.

As best shown in Figure 1, the lower portion of each member 23 is tapered, as at 24, in such manner that when the links are positioned inside of a tube 25 having a relatively sharp bend, as indicated at 26, Figure 3, the lower portions 24 of the "balls" 23 abut whereby the "balls" assume a comparative angular relation extending radially from the inner or lesser radius of the bend in the tube.

The outermost of the "balls" 23 contains a pin 20 passed through the bifurcations in the adjacent link 18, which outermost pin engages a tongue 27 extending from a shank 28 having a slight bend 29 therein in a direction toward the tapered portion 24 of the "balls" 23, and terminating in an enlarged head 30. A sliding "ball" member 31 of toric exterior configuration, as indicated at 32, is provided with a recessed socket 33 of a diameter to accommodate the head 30. The shank 28 extends into a frusto-conical recess 34 permitting relatively free bending movement 60 of the member 31 about the shank 28 when the

device is inserted into a tube in the process of bending the same. The relative sliding movement of the member 31 permits the insertion of the device into a tube for the formation of a bend of relatively small radius, as indicated in Figure 3.

A modified form of construction is disclosed in Figures 6 to 9 inclusive, adapted to be utilized in forming bends of slightly greater radius, and includes a plurality of "balls" 50, the innermost of which seats in a frusto-conical recess 51 in a tubular shank 52 provided with an annular shoulder 53 within a bore 54. A bolt 55 extends into the bore 54 and is provided with a nut 56 seated against the shoulder 53, the bolt 55 terminating in a tongue 57 adapted to be engaged between bifurcations 58 of a link member 59, being held therein by means of a pin 60 passing through suitable registering apertures in the tongue and bifurcations. The link 59 extends inwardly of the adjacent "ball" 50 and terminates in a tongue 61 engaged within the bifurcations 58 of the next link 59. Pins 62 hold each link and the tongue of the adjacent link in related assembly and seat in annular recesses 64 formed within each link in such manner that the links are freely rotatable with respect to the flexible shaft comprised of successive links 59. The bifurcated portions 58 of each link are cut away at their lower surfaces, as indicated at 65, in such manner as to permit relative bending of the arbor in the same manner as indicated in connection with the previously discussed modification.

In this form, each of the "balls" 50 includes a toroidal member provided with a flange 66 extending to overlying position over the reduced periphery of the next adjacent "ball," the flange 66 forming the outer extremity of a substantially frusto-conical interior recess 67 terminating in the annulus 64.

In this modification, the outermost link 59 includes an extending shank 68 provided with a head 30' adapted to seat in a recess 33' in a toroidal member generally indicated at 31' and having a frusto-conical recess 34' therein, corresponding in all respects to the previously discussed member 31 and serving an identical purpose.

From the foregoing, the mode of use of the device should now be readily apparent. The arbor, in either the form shown in Figure 1, or the form disclosed in Figure 6, is inserted in a tube to be bent, and pressure applied to the ends of the tube to form the bend in any desired conventional manner. Obviously, in the construction in Figure 1, the links may assume the position shown in Figure 3 with the bend, while in the device of Figure 6, a similar bend is permitted by virtue of the flanges 66 and their adjacent associated recesses 67.

Obviously, a relatively sharp bend may be formed, and equally obviously, the dislocation of a pin in such manner as to injure the interior of the tubing is substantially precluded by the fact that the pin in neither modification extends entirely through the adjacent torus.

Additionally, in the modification disclosed in Figures 6 to 9, inclusive, relatively free rotation of the "ball" members 50 relative to the pins 62 is permitted, thus substantially reducing the wear on any particular portion of the apparatus and providing an extremely durable and long-lived construction.

From the foregoing it will now be seen that there is herein provided an improved device which accomplishes all the objects of this in-

vention, and others, including many advantages of great practical utility and commercial importance.

Since various embodiments may be made of this inventive concept, and since various modifications may be made in the embodiments hereinbefore shown and described, it is to be understood that all matter herein is to be interpreted merely as illustrative and not in a limiting sense.

I claim:

1. A bending ball arbor, comprising a plurality of balls of substantially toroidal configuration, said balls each being formed with an axial bore therethrough, a plurality of links received in said bores, pins extending through said links to connect adjacent links together, the free ends of said pins extending laterally outwardly of each side of said links, and said bore of each ball being formed with a pair of diametrically-opposed longitudinally extending grooves, each of said grooves being closed at one end, and said free ends of a pin being received in each pair of grooves.

2. A bending ball arbor, comprising a plurality of balls of substantially toroidal configuration, said balls each being formed with an axial bore therethrough, a plurality of links received in said bores, pins extending through said links to connect adjacent links together, the free ends of said pins extending laterally outwardly of each side of said links, and said bore of each ball being formed with an enlarged annular recess providing with said bore a radially inwardly-directed annular shoulder, and the free ends of a pin being seated in each recess against the shoulder thereof.

3. A bending ball arbor, comprising a plurality of balls of substantially toroidal configuration, said balls each being formed with an axial bore therethrough, a plurality of links received in said bores, pins extending through said links to connect adjacent links together, the free ends of said pins extending laterally outwardly of each side of said links, and said bore of each ball being formed with recessed portions not extending to the outer periphery of the ball and providing seats for the free ends of one of said pins.

4. A bending ball arbor, comprising a plurality of balls of substantially toroidal configuration, said balls each being formed with an axial bore therethrough, a plurality of links received in said bores, pins extending through said links to connect adjacent links together, the free ends of said pins extending laterally outwardly of each side of said links, said bore of each ball being formed with an enlarged annular recess providing with said bore a radially inwardly-directed annular shoulder, the free ends of a pin being seated in each recess against the shoulder thereof, each ball having a front surface, and said recess opening through said front surface to provide means for inserting and removing said pins therefrom.
